US00D889421S

(12) **United States Design Patent** (10) **Patent No.:** **US D889,421 S**
Choi et al. (45) **Date of Patent:** ** *Jul. 7, 2020

(54) **LIGHT EMITTING DIODE PACKAGE**

(71) Applicant: **SEOUL SEMICONDUCTOR CO., LTD.**, Danwon-gu, Ansan-si, Gyeonggi-do (KR)

(72) Inventors: **SeungRi Choi**, Ansan-si (KR); **SeMin Bang**, Ansan-si (KR); **MyungHee Lee**, Ansan-si (KR)

(73) Assignee: **Seoul Semiconductor Co., Ltd.**, Ansan-si (KR)

(*) Notice: This patent is subject to a terminal disclaimer.

(**) Term: **15 Years**

(21) Appl. No.: **35/506,561**

(22) Filed: **Oct. 12, 2018**

(80) **Hague Agreement Data**

Int. Filing Date: **Oct. 12, 2018**

Int. Reg. No.: **DM/103805**

Int. Reg. Date: **Oct. 12, 2018**

Int. Reg. Pub. Date: **Apr. 12, 2019**

(30) **Foreign Application Priority Data**

Apr. 13, 2018 (KR) 30-2018-0017547

(51) **LOC (12) Cl.** **13-03**

(52) **U.S. Cl.**

USPC **D13/180**

(57) **CLAIM**

The ornamental design for light emitting diode package, as shown and described.

DESCRIPTION

1. Light emitting diode package

1.1 : Perspective

1.2 : Front

1.3 : Back

1.4 : Left

1.5 : Right

1.6 : Top

(Continued)

1.7 : Bottom

1 Claim, 7 Drawing Sheets
